[57] CLAIM

The ornamental design of a fishing reel, as shown and described.

DESCRIPTION

FIG. 1 is a left side elevation view of a fishing reel, showing my new design—the broken line showing of part of a fishing rod and line is for illustrative purposes only and forms no part of claimed design;
FIG. 2 is a left side elevation view thereof;
FIG. 3 is a front elevation view thereof;
FIG. 4 is a right side elevation view thereof;
FIG. 5 is a rear elevation view thereof;
FIG. 6 is a plan view thereof; and,
FIG. 7 is a bottom view thereof.
